FURNACE GRATE

Filed July 19, 1927

Inventor

Edward V. Wickey
By *Herbert E. Smith*
Attorney

UNITED STATES PATENT OFFICE

EDWARD V. WICKEY, OF SPOKANE, WASHINGTON, ASSIGNOR TO UNION IRON WORKS,
OF SPOKANE, WASHINGTON

FURNACE GRATE

Application filed July 19, 1927. Serial No. 206,853.

My present invention relates to improvements in furnace grates of the sectional type, wherein interlocking pairs of bearing bars are used in connection with separable grate 5 bar sections or fuel supports.

The primary object of my invention is the provision of means whereby the sectional grate bars and bearing bars may be manufactured at comparatively low cost, because 10 of the simplicity of construction and the minimum number of parts utilized in the grate. Due to the simplicity in construction and the minimum number of parts employed, repairs and replacements may be made with 15 facility, and the grate may be maintained in efficient and proficient condition at a comparatively low cost of maintenance.

My invention consists in certain novel combinations and arrangements of parts as will 20 hereinafter be more fully pointed out and claimed.

In the accompanying drawings, I have illustrated one complete example, and two slight modifications thereof, wherein the 25 parts are combined and arranged according to modes I have thus far devised for the practical application of the principles of my invention.

Figure 1 is a plan view of one of the 30 sectional grate members;

Fig. 2 is a view in side elevation showing the grate bars broken for convenience of illustration;

Fig. 3 is a plan view of the interlocking 35 bearing bars with the fuel supports or grate sections omitted;

Fig. 4 is a detail view showing a joint between adjoining sections of the grate;

Fig. 5 is a transverse sectional view at line 40 5-5 of Fig. 1;

Fig. 6 is a detail view in elevation of one end of the furnace grate bar showing a grate section in position to be applied to a bearing bar;

Fig. 7 is a detail view showing a modified 45 interlocking engagement between pairs of bearing bars; and

Fig. 8 is a modified form of joint between the grate sections.

In carrying out my invention, I utilize a

pair of bearing bars 1 and 2 which are interlocked at their ends and at a point intermediate of the ends. Each of these bars is provided with beveled faces 3 to permit ashes to fall through the grates without interruption, 55 and the ends of the interlocking bars are provided with complementary heads 4 and 5 while the intermediate portions of these bars are provided with complementary heads 6 and 7. The end heads and intermediate heads 60 are provided with interlocking tongues 8 and grooves 9 extending in vertical planes, and it will be apparent that the two parallel bars 1 and 2 are locked together by this engagement of the tongues and grooves. 65

The bearing bars are fashioned with openings or apertures 10 to provide for circulation of heated air currents as indicated in Fig. 2. The end heads 4 and 5 of each of the bearing bars are provided with supporting blocks 11 70 which rest upon the walls or bridges of the furnace in usual manner, and these supporting blocks are fashioned with beveled ends 12, as indicated in Fig. 2, to permit disposal 75 of the ashes.

In the upper faces of each of the bars 1 and 2 are provided squared or oblong sockets 13 which act as guides and retaining members for the sectional grate bars which are indicated as 14, 15 and 16. The end grate sections or fuel supports 14 and 16 are fashioned 80 with lugs 17 that slip into the sockets 13 of the bearing bars and prevent relative movement between the bearing bars and grate bar sections. 85

The adjoining grate sections are provided with overlapping joints that include lugs 18 and 19 as seen in Fig. 4, and these lugs provide a joint that will compensate for expansion or contraction of the grate sections due 90 to heat from the furnace.

In Fig. 8, a modified joint is shown where a pair of hooked lugs 20 and 21 are used on the adjoining grate sections, and these hooked lugs compensate for expansion and contraction of the adjoining grate sections. 95

In Fig. 7, the end heads 22 and 23 of the bearing bars are fashioned with tongues 24 and 25 that interlock as indicated, and in some instances, this interlocking joint may 100

be substituted for the joint shown in Fig. 3.

It will be apparent that the parts that become warped or worn and require replacement, may readily be separated and detached from remaining parts, and replacements and repairs may be made with facility. The simplicity of construction provides for facility in assembling the grate, and also in dismantling the grate when necessary.

10 Having thus fully described my invention, what I claim as new and desire to secure by Letters Patent is—

15 1. The combination with a pair of bearing bars each having integral lateral heads and complementary interlocking tongues and grooves on adjoining faces of said heads, of removable grate-bar end sections and an intermediate section, co-acting retaining means on the end sections and bearing bars, and co-acting retaining means between said sections.

20 2. In a furnace grate the combination with removable grate bar sections, of a pair of bearing bars, complementary, laterally projecting heads integral with each of said bars, and complementary tongues and grooves on adjoining faces of said heads.

In testimony whereof I affix my signature.
EDWARD V. WICKEY.
